UNITED STATES PATENT OFFICE.

ROSWELL COVERT PICKETT, OF WARRENVILLE, AND HARRY WARD THOMPSON, OF CHICAGO, ILLINOIS, ASSIGNEES TO ADVERTISERS SERVICE BUREAU, OF CHICAGO, ILLINOIS.

FORM-ROLLER CONTROL AND TIMING DEVICE.

Application filed November 8, 1926. Serial No. 147,108.

The object of our invention is to provide a form roller control and timing device for duplicating or printing machines.

More particularly, it is our object to provide a mechanism including a series of inking rollers and means for controlling them, whereby a duplicating or printing machine may be used for printing in a variety of arrangements and of colors.

10 In this connection, it is our purpose to provide means in the form of controlling mechanism for form inking rollers, whereby the rollers may be controlled, and to provide an attachment for the duplicating machine 15 drum or cylinder for cooperation with the rollers, whereby matter may be printed on a letter sheet or the like in such a variety of colors and arrangements as may be desired.

20 With these and other objects in view, our invention consists in the construction, arrangement and combination of the various parts of our form roller control for printing machines, whereby the objects contemplated are attained, as hereinafter more fully set 25 forth, pointed out in our claims, and illustrated in the accompanying drawings, in which:

Figure 1 is an end elevation of a printing machine equipped with an apparatus embodying our invention.

30 Figure 2 is a top or plan view of a part of the machine.

Figure 3 is a detail, sectional view taken on the line 3—3 of Figure 2.

35 Figure 4 is a detail, sectional view taken on the line 4—4 of Figure 3.

Figure 5 is a detail, sectional view taken on the line 5—5 of Figure 1.

40 Figure 6 is a detail, sectional view taken on the line 6—6 of Figure 3; and.

Figures 7, 8, 9 and 10 are plan views showing diagrammatically sheets of paper with matter thereon to illustrate the work done by the machine embodying our improvements.

45 In the accompanying drawings, we have shown a printing machine having the ordinary base indicated by the reference numeral 10 supporting the frame 11. Mounted in the frame is a shaft 12 on which is supported a hub 13, having the projecting spokes or arms 14, terminating in end rings 15, which are connected by longitudinally arranged rods or the like 16.

The hub, spokes and rings form the frame

of a drum or cylinder, which is completed 55 when the type form support indicated generally at A is mounted thereon.

The rings 15 are preferably in the form of angle iron as shown in Figure 6.

With the printing machine of this type, 60 there is ordinarily used a printing form in the form of a section of a drum or cylinder surface, indicated at 16^a, having the type 17 in its surface.

The outer edges or ends of the form 16^a 65 rest on the rings 15 and just inside the rings, the form is provided with inwardly extending flanges 18.

The printing form or type form support A usually has a rod 19 connecting the flanges 70 18. Pivoted to the rod 19 are curved spring fasteners 20 adapted to be snapped around the shaft 12 for holding the form A in place.

In certain standard machines of this kind, means are provided for printing from the 75 type through a ribbon or for inking the type when the ribbon is removed.

There can thus be produced a letter made in imitation of a typewritten letter or a 80 letter printed from printer's ink.

For printing with ink, a set of inking rollers shown generally at B in Figure 3 is provided.

The printing form cooperates with a printing roller 21.

The ink distributing means B includes a 85 supporting frame 22, an ink reservoir 23, a series of distributing rollers 24, 25, 26, 27 and 28, and a pair of spaced inking rollers 29 and 30.

There is usually provided with such a standard machine a signature attachment 31, shown in Figure 1.

The parts just described are standard parts and in themselves form no part of our present invention.

With these standard parts, the body of the letter may be printed through the ribbon or with ink and the signature may be attached in a different color.

Our invention involves the idea of providing an additional type form and providing means for adjusting the rollers 29 and 30 for inking the additional type form only for printing part of a letter sheet in ink, while 105 permitting the remainder to be printed through the ribbon and permitting also the usual use of the signature attachment.

By means of our invention, it is possible in addition to the results obtained by the standard duplicating machine to print in ink in a variety of places on the letter sheet.

5 In Figure 7, we have shown for purposes of illustration a sheet of letter paper 32, having the head 33, the body 34 and the signature 35. With the ordinary duplicating machine, the sheets are used having the heading printed thereon, and the machine can be used for printing the body of the letter through the ribbon or with ink, and in either case for printing the signature in a different color.

With our device, the heading can be printed on the duplicating machine.

15 In Figure 8, we have shown a sheet 32 with the heading, body and signature as explained and with margins 36. These margins may be printed by our device in a color different from 20 that of any of the other parts.

25 In Figure 9, we have shown a sheet with only one margin and in Figure 10 a sheet with a body, a margin and a coupon. The body, margin and coupon may be printed in different colors by the use of our invention.

It will thus be seen that by the use of our device, it is possible to print in addition to the body and signature, which can be done with the ordinary duplicating machine, margins or headings, coupons and so on in different colors.

30 For accomplishing our purpose, we provide a separate type form section C, which may extend circumferentially of the rotary member as far as may be desired for the purpose of carrying the desired type, cuts or other material.

35 The type form C is arranged so that its ends may rest on the rings 15, as shown in Figure 6, in the same manner as do the ends of the type form A.

40 The form C has the inwardly, projecting flanges 37 adjacent to the rings 15. These flanges are connected by a rod 38. Spring 45 clip devices 39 are pivoted to the rod 38 and may be snapped around another rod 40. The rod 40 extends between two brackets or arms 41, which are secured to the rings 15 in one of the spokes 14, as shown in Figures 1 45 and 6.

45 Preferably two of the parallel spokes have supported thereon stops 42 for engaging the edge of the type form C for preventing its sliding circumferentially of the rotary member.

50 In the ordinary duplicating machine, there are provided the ribbon spools 43 and 44 mounted on spindles 45^a. The ribbon 46^a is threaded from one spool 43 around the outer surface of the type form A and thence to the other spool 44.

55 The type forms A and C are spaced apart far enough to allow clearance for the ribbon.

60 For inking the type form C, we use the regular equipment, except that we provide

means for adjusting the rollers 29 and 30 and sometimes use partitions in the ink reservoir 23.

65 The means for adjusting the rollers 29 and 30 make it possible to move them to position 70 where they contact with and ink the type carried by the form C and then move to inoperative position.

75 For securing the adjustment just mentioned and synchronizing the adjustment with the operation of the rotary member, we mount the rollers 29 and 30 in the following manner:

80 These rollers as shown in Figure 4 have the shafts 45 and 46 extending lengthwise through them. These shafts 45 and 46 have at their ends eccentric spindles. The spindles for the shaft 45, as shown at 47 and 48 are mounted in suitable bearings in the frame 22.

85 The spindles 49 and 50 of the shaft 46 are likewise mounted in bearings in the frame 22.

90 It will be seen that by rotating the spindles in their bearings, the rollers may be adjusted toward or from the rotary member of the multigraph machine, for thus causing them to be in position to ink the printing surfaces or in positions spaced from the path of the printing surfaces, depending upon the adjustment of the rollers.

95 The spindles 48 and 50 project beyond the bearings in which they are mounted.

100 We will now describe the mechanism for imparting limited rotation to the spindles for adjusting the rollers.

105 The mechanisms for the two spindles are the same, except as to the cams hereinafter mentioned.

110 Each spindle has at its outer end beyond the bearing in which it is mounted a head 51 provided with a screw-threaded recess 52. Screwed into the recess 52 is a cap screw 53, having a portion of its shank smooth as at 53^a.

115 Supported on the smooth portion of the cap screw 52 and gripped between its head and the head 51 is a pinion 54, having a small extended hub 55 terminating in a head 56. The cap screw can be loosened for adjusting the pinion 54 rotatably on the cap screw, and the cap screw can then be tightened for holding the pinion against rotation with relation to the spindle 48 or spindle 50 as the case may be.

120 Mounted on the frame 22 near each spindle 48 and 50 is a lug 57 into which is screwed a cap screw or the like 58, having a smooth shank portion 59. Rotatably mounted on the shank portion 59 is a plate 60, which has a large slot 61 receiving the portion 55 of the hub of the pinion 54. The portion of the plate 60 along one edge of the slot 61 travels between the pinion 54 and the enlarged head 56.

125 Supported on the plate 60 in mesh with the

teeth of the pinion 54 is a rack bar 62. By rocking the plate 60 on its pivot screw 58, the movement of the rack bar 62 will rotate the pinion 54 and the spindle 48 for thus rotating the shaft 45 and roller 29 for moving the eccentrically mounted roller toward or from position where it will serve to ink the printing surfaces.

On the frame 11 is a bracket 63 for each plate 60. A spring 64 is supported by the bracket 63 and connected with the plate 60 in such manner as to hold that plate in such position of its rocking movement as to cause the coating roller 29 or 30 as the case may be, to be held yieldingly in inoperative position.

Thus with the mechanism as described up to this point, it will be seen that when the rotary member of the duplicating machine rotates, the rollers 29 and 30 will be yieldingly held out of inking contact.

We will now describe the means for moving the rollers 29 and 30 to inking position at the proper time during the rotation of the rotary member of the duplicating machine.

25 On the shaft 12, there is mounted a cam 65 for operating the roller 29 and a cam 66 for operating the roller 30.

Pivoted between its ends on a stud 67 is a rocker arm 68 on one end of which is a roller 30 69 for traveling on the cam 65. The other end of the rocker arm 68 engages a roller 70 on the plate 60 for the roller 29.

The parts just described are so arranged that during the rotation of the rotary member carrying the type form, the portion 65^a of the cam 65 will actuate the arm 68 at the proper time to cause the plate 60 to be rocked for moving the roller 29 to inking position.

In Figure 3, the roller 29 is shown in this inking position.

After the roller 29 has inked the type surfaces of the form C, the roller 69 of the arm 68 clears the portion 65^a of the cam 65 and the appropriate spring 64 actuates the plate 60 for moving the roller 29 to inoperative position.

The cam 66 has a portion 66^a for similarly cooperating with a similarly mounted rocker arm 68^a for actuating the plate 60 for the roller 30 for causing that roller to be moved to position for inking the type surface of the form C and to permit the spring 64^a similar to the spring 64 to actuate the appropriate plate 60 for moving the roller 30 to inoperative position when the roller on the arm 68^a leaves the portion 66^a of the cam 66.

It will thus be seen that if the operator of the machine desires to print the body of a letter, as shown in Figure 7, through the inking ribbon 46^a, and desires to print a heading 33, he may do so.

The matter for the heading is arranged on the printing form C, which is inked from the rollers 29 and 30. Then as the paper is fed between the roller 21 and the rotary member

of the machine, the heading 33 of the sheet 32 is printed from the form C and the body 34 is printed through a ribbon from the form A.

If it is desired to print something at the bottom of the sheet, as for instance the coupon shown in Figure 10, the type matter of forms A and C are reversed (set upside down) so that the top of the sheet will be printed first as it goes through the machine. It is customary to feed the sheets into the machine bottom edge first.

The roller 30 is used for printing marginal matter. For that reason, it is cut away at its center as indicated at 70 (Figure 4) to leave only the ends of the roller of larger 80 diameter than the intermediate body portion thereof. I then provide in the ink reservoir 23, the partitions 71 shown in Figure 2. Ink from these partitions will be supplied through the intermediate rollers shown in 85 Figure 3 to the end portions of the roller 30 for thus inking only the ends of the type surface of the forms C and A. Usually the margin to be printed runs down the entire side of the body of the letter. Therefore, the timing mechanism is inoperative, leaving 90 form roller stationary. Rarely do we print a margin, or two colors, on form C alone, although this is possible to do.

It is unnecessary to avoid inking the entire 95 length of the roller 29.

It is necessary to prevent mixing of different colors of ink due to the reciprocating movement of the rollers 26 and 28.

This is done in the following simple manner:

(a) Partitions 71 are used to separate colors of ink in the ink fountain 23.

(b) A very narrow slot or groove is cut in rollers 25, 27 and 29, just opposite the partitions 71 so that the ink on one side of each partition will not mix with the ink on the other side thereof. The roller 30 is cut away at 70 so that only that portion of the roller opposite the margin to be printed being left. 105 110

(c) Then grooves or slots are cut in the reciprocating rollers 26 and 28 which are just wide enough so that the reciprocating movement of these rollers does not cause the ends of the inking surfaces to travel across 115 the grooves of the rollers 25, 27 and 29 and thereby prevents mixing of the blue ink for the heading and the red ink for the margin, for instance.

We will now review briefly how a variety of 120 products may be made by the use of our controlling mechanism.

If it is desired to print a letter body and signature to get the result ordinarily secured with a duplicating machine, the form C may 125 be left off of the machine, and the body of the letter may be printed from the form A through a ribbon and the signature printed with the signature attachment 31.

If it is desired to print the body of the let- 130

ter with ink and to use the signature attachment, the arm 68 may be removed, and the roller 29 adjusted to inking position by loosening the cap screw 53 and rotating the spindles 47 and 48 in their bearings and then tightening the cap screw, no ribbon being used.

If it is desired to print a heading in addition to printing the body, both in ink, this 10 can be done by putting the matter for the heading on the form C and using that form. It will be understood that the signature attachment can be used in this case.

If it is desired to print a head on a letter 15 with ink and print the body through the ribbon, this can be done in the manner already explained with our attachment, using the roller 29 to ink the type matter on the form C for the heading.

20 As already explained, the matter on the form C may be used for printing something at the bottom of the letter sheet.

Whether a heading or a footing or coupon or the like be printed, it is still possible to 25 use the signature attachment when desired. If the user wants to print marginal matter, the roller 30 is employed with our operating attachment, and suitable partitions 71 are used.

30 It will thus be seen that with our attachment a great variety of results is obtainable, as suggested by the following:

1. Ribbon printed body and signature in the same or different colors.

35 2. Ink printed body and signature in different colors.

3. Ink printed body and heading in one color with or without signature in another color.

40 4. Ribbon printed body and ink printed heading in different colors with or without signature in still another color.

5. Ribbon printed body and ink printed footing in different colors with or without

45 signature in a third color.

6. Ink printed body and ink printed footing in the same color, with or without signature in a different color.

50 Any of the above combinations with one or two margins.

It is thus seen that we have provided a rather simple and inexpensive structure whereby the range of utility of an ordinary duplicating machine is very much enlarged.

55 A feature of our device which has some importance may now be mentioned.

It will be noted that the type form C rests on the rings 15 and is held in position by the clips 39. The clips 39 are of spring material

60 and are so shaped as to yieldingly clip the type form C against the rings 15.

For allowing an accurate adjustment and an accurate variation in adjustment, I provide at each corner of the type form C an adjusting or set screw 72. By adjusting the

various screws 72, it will be seen that an accurate adjustment of the type faces on the form C may be secured.

From our description, it can be readily seen that our improvement, with slight modification, can be made adaptable to a large number of machines of standard make, and in this way our device is adaptable for many purposes not evident from the reading of our description, but it is our intention to include the adaptability of our device to as general an application as possible.

We claim as our invention:

1. In a printing machine, a rotary element, 80 having a plurality of printing forms thereon, means for printing from the forms on a sheet, a body portion printed through a ribbon, an end portion from inked type surfaces, and a marginal portion at the side of the body portion from inked type surfaces and means comprising an inking roller having its central portion cut away whereby its end portion inks the marginal type surfaces.

2. In a printing machine, a rotary element, 90 having a plurality of printing forms thereon, a ribbon, a printing roller and a plurality of inking rollers, and means for automatically moving the rollers to and from inking position for printing a portion of the sheet through the ribbon and other portions from different inked surfaces for thus printing a letter head, a letter body and marginal matter in different colors one of said inking rollers being adapted to ink the marginal printing form and having its central portion cut away to clear the ribbon covered printing form.

3. In a machine of the class described, a 105 rotary member adapted to carry printing forms, printing forms supported on said member, an inking roller having spindles at its ends suitably journaled, the roller being eccentrically mounted with relation to the spindles, a pinion on one of the spindles, a rocking plate having a rack for coacting with the pinion, and means actuated from the rotary member for locking said plate.

4. In a machine of the class described, a 110 rotary member adapted to carry printing forms, printing forms supported on said member, an inking roller having spindles at its ends suitably journaled, the roller being eccentrically mounted with relation to the spindles, a pinion on one of the spindles, a rocking plate having a rack for coacting with the pinion, a cam on said rotary member, an arm pivotally mounted having one end arranged to coact with said cam and the other end arranged to coact with said plate.

5. In a machine of the class described, a 115 rotary member adapted to carry printing forms, printing forms supported on said member, an inking roller having spindles at its ends suitably journaled, the roller being eccentrically mounted with relation to the spindles, a pinion on one of the spindles, a 120 rocking plate having a rack for coacting with the pinion, a cam on said rotary member, an arm pivotally mounted having one end arranged to coact with said cam and the other end arranged to coact with said plate.

6. In a machine of the class described, a 125 rotary member adapted to carry printing forms, printing forms supported on said member, an inking roller having spindles at its ends suitably journaled, the roller being eccentrically mounted with relation to the

- spindles, a pinion on one of the spindles, a rocking plate having a rack for coacting with the pinion, a cam on said rotary member, an arm pivotally mounted having one end ar- 5 ranged to coact with said cam and the other end arranged to coact with said plate, and means tending to yieldingly actuate the plate to position for holding the inking roller in inoperative position.
- 10 6. In a machine of the class described, a rotary printing element having a type form thereon, an inking roller having spindles suitably journaled, said roller being eccentrically mounted with relation to the spindles, a pin- 15 ion on one of the spindles, a pivotally mounted rocking plate having a rack for coacting with the pinion, a spring for holding the plate in one position of its movement, an arm pivoted between its ends, said arm and plate having coacting parts whereby the rocking of the arm effects rocking of the plate, and means for rocking said arm from the rotary member.
- 20 7. In a machine of the class described, a rotary printing element having a type form thereon, an inking roller having spindles suitably journaled, said roller being eccentrici- 25
- cally mounted with relation to the spindles, a pinion on one of the spindles, a pivotally mounted rocking plate having a rack for co- 30 acting with the pinion, a spring for holding the plate in one position of its movement, an arm pivoted between its ends, said arm and plate having coacting parts whereby the rock- 35 ing of the arm effects rocking of the plate, and means for rocking said arm from the rotary member, comprising a cam on the rotary member and a coacting member on the arm.
8. In a printing machine, a rotary element, printing forms carried thereby, a ribbon over 40 a portion of one of said forms, an inking roller for the portion of said form not cov- 45 ered by the ribbon, a second inking roller for the other form, means comprising an ink reservoir divided into a plurality of compart- 50 ments for supplying different colored inks to said rollers, and means cooperatively associated with the rotary element for causing the inking rollers to be moved toward the printing forms only when the desired form is in position to be inked by its respective roller.

Des Moines, Iowa, October 20, 1926.

ROSWELL COVERT PICKETT.

HARRY WARD THOMPSON.
